UNITED STATES PATENT OFFICE.

EDGAR E. BROSIUS, OF PITTSBURGH, PENNSYLVANIA.

GRAB BUCKET.

Application filed April 10, 1925. Serial No. 22,207.

The present invention relates broadly to material handling apparatus, and more particularly to apparatus of the so-called excavating or grab bucket type comprising 5 openable sections.

It is customary at the present time in the art to which the present invention relates to provide buckets both of the single line and two line type. In the use of such single line 10 buckets it has frequently been found that a comparatively large body will become lodged between the edges of the bucket sections and prevent complete closing thereof. Later, when the bucket is tripped, a considerable 15 relative movement occurs between the cross head and the bucket before the cross head is checked by the bucket. If the bucket is handling a heavy load, it is readily apparent that the checking of this relative movement 20 will throw a sudden strain, not only on the bucket parts, but also on the hoist cable, the strain frequently being enough to snap the cable.

In the larger installations utilizing two 25 lines this disadvantage is eliminated by permitting the hold line to hold the bucket while the other line is being payed out to open the bucket. The same is likewise true of buckets of the type having a motor in the head of the 30 bucket for operating the bucket sections. I am not aware, however, that it has heretofore been considered feasible to provide any construction adaptable to single line buckets for positively controlling the opening movement 35 to eliminate such sudden shocks, and enable checking of the opening movement at any point from closed position to fully opened position.

The present invention has for certain of 40 its objects, therefore, the construction of a grab bucket, and more particularly of the single line type, having means for preventing the possibility of sudden shocks during the opening movement of the bucket, and 45 enabling the checking or stopping of the opening movement at will.

Another object of the present invention is to provide a form of bucket control adapted to be applied at will to standard bucket 50 structures, or to be incorporated in new buckets.

In the accompanying drawings I have shown for purposes of illustration only, a preferred embodiment of the present invention, it being understood that the drawings do 55

not define the limits of my invention, as changes in the construction and operation disclosed therein may be made without departing either from the spirit of the invention or the scope of my broader claims. 60

In the drawings:

Figure 1 is a side elevational view of a bucket embodying the present invention, the bucket sections being shown in opened position; 65

Figure 2 is a view similar to Figure 1, the bucket sections, however, being shown in closed position, and a portion of the control section being broken away.

Figure 3 is a front elevation of the construction illustrated in Figure 2; 70

Figure 4 is a top plan view of the construction illustrated in Figure 2;

Figure 5 is a detail transverse sectional view on an enlarged scale on the line V—V 75 of Figure 2, and

Figure 6 is a sectional view of a valve mechanism for controlling the operation of the bucket.

In illustrating the present invention I have 80 elected to show a bucket of the general character described in my prior Patent No. 1,228,526 of June 5, 1917, although the utility of the invention is not limited to buckets of this specific construction or operation. 85

In carrying out the present invention there may be provided a bucket comprising sections 2 and 3 each having projecting bearing brackets 4 and 5 respectively, which are in turn provided with bearing portions 6 and 7 adapted to be brought into alignment for the reception of a shaft 8. This shaft is preferably a continuous one extending transversely of the bucket and providing a pivotal connection between the sections during their opening 90 and closing movements. In accordance with the present invention the bearing portions 6 may be connected by an intermediate centering guard 9. The shaft and bearing portions 6 may be secured against relative movement, and the bearing portions 7 left free to rotate on the shaft 8. In this case there may be secured to the shaft between the sides of the guard 9 a crank arm 10 adapted to move in unison with the section 2, the bearing 95 bracket 4, the bearing portions 6, the shaft 8 and the guard 9 as the bucket sections move from one position to the other. If desired, however, the bearing portions 7 may be secured against rotation on the shaft 8, while 100

the bearing portions 6 may be secured against rotation on the shaft 8, while 110

the shaft is free to rotate in the portions 6, the crank being secured to the portions 6 for movement therewith, this latter structure being preferable due to the relatively smaller bearing surfaces of the portions 7. The particular construction in this respect is relatively immaterial, as it is only essential that the crank arm 10 move concomitantly with one of the bucket sections.

10 The outer corners of each of the sections 2 and 3 are pivotally connected to links 11 and 12 respectively. The links 11 are preferably extended at their upper ends in the form of pairs of spaced substantially horizontally 15 projecting plates 13. The free ends of the plates 13 are connected by a transversely extending pivot shaft 14, and the upper ends of the links 12 are pivotally carried by this shaft. The pivotal connection between the lower 20 ends of the links 12 and the bucket section 3 may comprise short pins 15, while the connection for the lower ends of the links 11 is preferably formed by a continuous pivot shaft 16. Cooperating with the links 11 for 25 bracing the same are angularly extending braces 17 connected at their lower ends to the central upper outer portion of the section 2, and at their upper ends to the horizontal plates 13.

30 Journaled between each pair of plates 13 is a sheave 18 having one face directly in the vertical plane of the shaft 8. Freely movable between the links 11 and 12 from the dotted line position of Figure 1 to the full line position of Figure 2, is a cross head 19 having journaled in its outer end sheaves 20 having their outer faces in the vertical plane of the respective sheaves 18. The cross head 19 is provided with vertically extending openings 40 21 for the passage of cables 22 which extend downwardly through the cross head and then divide, one passing below each of the sheaves 20 and thence upwardly over the corresponding sheaves 18, from which they pass downwardly to the cross head where they may be dead ended. The cables may have the usual eye 22^a for a crane hook.

Pivoted at one end to the mounting 23 on the lower side of the cross head, and 50 at its opposite end to the shaft 16, is a cross head guide lever 23'. Intermediate its ends this guide lever is bifurcated and provided with trunnion mountings 24 for a cylinder 25. This cylinder may be of the so-called cataract 55 type adapted to contain oil or other non-compressible fluid. Working within the cylinder is a piston having a piston rod 26 pivotally connected at its lower end to the outer end of the crank arm 10.

60 Extending from end to end of the cylinder 25 and forming a bypass between the opposite ends thereof, is a bypass 27 having intermediate its length a controlling valve 27^a which is normally urged toward closed position 65 in any desired manner as by a spring

shown in Figure 6. Cooperating with the valve is an operating pulley 28 adapted to be actuated by a control line 29 for opening the valve to any extent desired by merely pulling on the control line.

In operation, it may be assumed that the parts are in the position illustrated in Figure 2, the bucket having elevated its load and moved it to the point of discharge. The control line is pulled to open the valve 27^a. This 70 permits the fluid within the cylinder 25 to flow from the lower end thereof to the upper end, thereby permitting the piston rod 26 to lower at a speed directly controllable by the opening of the valve 27^a. As the piston rod 80 is connected to the crank arm 10, which in turn is connected to one of the bucket sections, herein illustrated as the section 2, with which it is always adapted to move in unison, it will be apparent that the descent of the piston rod controls the opening movement of the bucket sections, these sections always tending to open under the influence of gravity. If the valve 27^a is held open for a long 85 enough period of time, the sections will move to the position shown in Figure 1, while if the valve is released the sections may be positively stopped in their opening movement at any desired intermediate point. In this manner, the speed of opening movement is always 90 under the direct and positive control of the operator, and the bucket and hoist cable need never be subjected to any sudden shocks. This constitutes a very valuable feature of the present invention.

100 After the bucket has been permitted to discharge, the hoist cable is lowered, thereby lowering the bucket until it rests in open position on the material to be handled. At this time the weight of the bucket will be relieved from the cables 22, thereby permitting the cross head to move from its dotted line position of Figure 1 to its full line position of this figure, this movement being permitted by a one-way operating check valve 30 adapted to 105 open upon upward movement of the piston to permit the fluid to pass freely through the piston. During this movement, the pivotal connection 23 will describe the arc A, while the axis of the trunnions 24 will describe the 110 arc B. The cylinder 25 will assume the successive positions indicated in Figure 1, the weight of the cross head being sufficient to cause the piston rod to move upwardly in the cylinder and displace fluid from the upper 115 into the lower end through the check valve 30. When the parts have reached the position shown in full lines in Figure 1, and the hoist cable is taken up the cross head will tend to 120 return from its full line position of Figure 1 to the position shown in Figure 2. During this time there is a powerful closing and digging action exerted on the sections by reason of the 3 to 1 reduction obtained by the sheaves 18 and 20. With the valve 27^a closed, the 125 130

fluid in the cylinder 25 will form a positive lock against any accidental movement of the bucket sections toward open position.

The cylinder 25 and its cooperating mechanism constitutes a self-effective or non-power means acting in effect as a brake, thereby distinguishing from an electric motor or the like which is not self-effective but which requires connection with an external source of power. The braking means herein disclosed is normally effective, while a motor of the character heretofore utilized is normally ineffective. It will be readily apparent to those skilled in the art that a self-effective means may assume many different embodiments, and I therefore use the expression generically as definitive of the general type of mechanism. Furthermore, the bucket sections herein shown are movable to closed position by the suspending means, thereby further distinguishing from power motor structures in which the motor effects closing movement.

The advantages of the present invention arise from the provision of a bucket having means independently of the hoist cable and not requiring any external power for positively controlling the opening movement of the bucket sections.

Further advantages arise from the provision of a single line gravity opening bucket having means for positively controlling the opening speed of the bucket.

I claim:

1. In a bucket, openable sections, suspending means for the bucket operable for closing said sections, and means carried by the bucket for controlling the opening speed of the sections and biased to lock the sections against movement.

2. In a bucket, openable sections, suspending means for the bucket operable for closing said sections, and fluid pressure means carried by the bucket for controlling the opening speed of the sections and for locking the sections in any desired position.

3. In a bucket, openable sections, a single suspending means for the bucket operable for closing said sections, and means connected at one end only to the bucket and movable relatively to said single suspending means for controlling the opening speed of the sections.

4. In a bucket, openable sections, hydraulic means for holding said sections closed, a bypass for said means, and a release valve for said bypass to permit the sections to gradually open.

5. In a bucket, openable sections, hydraulic means for holding said sections closed, and a bypass for said hydraulic means to permit the sections to gradually open.

6. Material handling apparatus, comprising a single line bucket having sections adapted to be moved to closed position by said

single line, and hydraulic means having a controllable by-pass for controlling the opening movement of the sections.

7. Material handling apparatus, comprising a bucket having openable sections, and self-effective means for either locking said sections in predetermined position or controlling the opening movement of said sections.

8. Material handling apparatus, comprising a bucket having openable sections, and self-effective means for variably controlling the opening movement of said sections at will throughout the entire opening movement thereof.

9. Material handling apparatus, comprising a bucket having openable sections, self-effective means for variably controlling the opening movement of said sections at will, and suspending means for said bucket effective for closing said sections.

10. Material handling apparatus, comprising a single line bucket having sections adapted to be moved to closed position, a pivotally mounted control cylinder cooperating with said bucket for controlling the opening movement of the sections and moving relative to a plane passing substantially through engaging surfaces of the bucket sections when in their closed positions, a piston in said cylinder, and a means operatively connecting the piston and one end of the cylinder only to said bucket.

11. In a bucket, openable sections, a hydraulic cylinder for holding said sections closed, said cylinder being connected at one end only to said bucket, and a by-pass for said cylinder to permit the sections to gradually open.

12. In a bucket, openable sections and hydraulic means for controlling the operation of the sections, the hydraulic means comprising a bypass for controlling the opening movement of the sections, and a valve permitting free resetting of the hydraulic means at another stage in the operation of the sections.

13. In a bucket, openable sections and hydraulic means for controlling the operation of the sections, the hydraulic means comprising a bypass and a valve normally urged to closed position disposed in the bypass whereby the sections may be permitted to open or lock in a definite position upon the manipulation of the valve.

14. In a bucket, openable sections and hydraulic means for controlling the operation of the sections, the hydraulic means comprising a bypass for permitting opening movement of the sections and for locking the sections against movement at will independently of the position of the bucket.

In testimony whereof I have hereunto set my hand.
